MECHANISM FOR MAKING BUNCH CHARGES

Joseph W. Giles and William J. Giles, Belleville,
N. J., assignors to Jersey Cigar Machines, Inc.,
Belleville, N. J.

Application February 25, 1941, Serial No. 380,480

8 Claims. (Cl. 131—81)

The primary object of our invention is to devise a novel mechanism to accurately measure the depth of filler in a chamber in which it is being assembled in small quantities to build up a complete bunch charge.

Each small quantity is pressed to the bottom of the sizing chamber before the next small quantity is fed into the sizing chamber. This causes the bunch charges to have a constant density, so that the bunches will be of uniform size and density.

The bottom of the sizing chamber has a closure which is held in a positively closed position during the operation of building up a bunch charge. To obtain these results, novel mechanism is employed to control under spring pressure the sizing operations.

As soon as the bunch charge is built up to the required height, the sizing plunger causes a trip mechanism to operate to stop the feed of filler, and to release the bottom closure of the chamber in which the bunch charge has been built up. An ejecting plunger moves the tobacco from the chamber to the rolling apron for the application of a binder in the conventional manner.

It has heretofore been customary in bunch making machines to feed the filler in large quantities, and to cut it off to form bunch charges which were not uniform in size or density, due to the fact that a mass of tobacco in a channel or passage will, when pushed forwardly by a plunger, pile up and cause friction against the walls of the passage. The tobacco near the plunger receives excessive pressure, while the forward portion of the tobacco will receive less pressure and be of less density. These objectionable features have been overcome in our present invention.

With the above and other objects in view which will hereinafter clearly appear, our invention comprehends novel mechanism for making cigar bunch charges from either long or short filler.

Other novel features of construction and advantage will be set forth in the detailed description and the appended claims.

For the purpose of illustrating the invention, we have shown in the accompanying drawings a preferred embodiment of it, which, in practice, will give satisfactory and reliable results. It is, however, to be understood that this embodiment is typical only and the various instrumentalities of which our invention consists can be variously arranged and organized, and the invention is not limited to the exact arrangement and organization of these instrumentalities as herein set forth.

Figure 1 is a top plan view of mechanism for

making cigar bunch charges, embodying our invention.

Figure 2 is a side elevation.

Figure 3 is a side elevation, partly in section, partly broken away, and showing certain of the parts in a different relation from that seen in Fig. 2, and in tripped position.

Figure 4 is a side elevation, partly in section, showing parts seen in Figures 2 and 3 in a position they assume before being tripped.

Similar numerals indicate corresponding parts. Referring to the drawings:

1 designates the frame of the machine, which may vary widely in contour and construction.

15 A driven belt 2 drives a pulley 3 to drive a shaft 4 which is connected by a clutch 5 with a shaft 6 to drive the latter. The shaft 6 is intergeared with a shaft 7 having fixed to it a crank 8 which actuates a link 9 to rock a lever 10, loosely mounted on a rock shaft 11. The lever 10 has an arm 12 to which one end of a spring 13 is fixed, the other end of said spring being fixed to a lever 14 fixed on the rock shaft 11, thereby effecting the rocking of the shaft 11 and the actuation of a

20 sizing plunger 15. A trip lever 16 is pivotally carried by the lever 14 and is held by a spring 17 against a stop 18, which latter is part of the lever 14. The arm 12 of the lever 10 has an adjustable screw 19 adapted at a certain time to 25 contact the trip lever 16. The screw 19 is adjustable to determine the height of a single bunch charge. To increase the height of a bunch charge, the screw is advanced, and to decrease such height the screw is retracted.

30 A pin 20 on the lever 14 overhangs the lever 10 and the spring 13 tends to move the lever 10 towards the stop 20.

21 is a sizing or measuring box to which small quantities of filler tobacco are intermittently fed, 40 and the lower end of its tobacco receiving chamber is closed by a lever 22 fixed to a rock shaft 23 journaled in the frame 1.

A detent lever 24 is fixed to the shaft 23, and has a trip arm 25 which bears against a hook 45 26 at one end of a lever 27 loosely mounted on a stud 28. The lever 27 is retained in its raised position by a spring 29. A spring 30 tends to return the lever 24 to its upward position so that the arm 25 will be in a position to be engaged by 50 the hook 26.

The lever 27 is released by a link 31 pivoted to it and to a cam lever 32 controlled by a cam 33 on a cam 34 fixed on a shaft 35 and driven by a sprocket 36 and a sprocket chain 37. A stop lever 55 38 is loosely mounted on the rock shaft 23 and

has an arm 39 contacting with the lever 16 to move the lever 38 away from a lever 40, the lever 40 being moved in the opposite direction by a spring 53. The lever 40 is pivotally supported at its upper end and is connected by a link 41 with a three armed lever 42, pivoted at 43 and having one arm connected by a link 44 with a lever 45 fulcrumed at 46 on an arm 49. The lever 45 has a roller 47, cooperating with a cam 48 on the shaft 7.

A clutch lever 49 pivoted at 50 has a clutch arm 51 controlling engagement of the discs of the clutch 5.

The tobacco, either long or short filler, is intermittently fed in small quantities, in any desired manner, on a plate 52 from which each small quantity is removed by a pusher to the sizing or measuring chamber, in a similar manner to that shown in our copending application, Serial No. 372,058, or in any other desired manner.

The lever 38 is retained in raised position by a spring 54 which tends to rock the lever 38 upwardly against a stop 55.

The tobacco is fed in small quantities in any desired manner to the plate 52, and is intermittently fed from the plate to the sizing box in the following manner. The shaft 7 has a crank 56 fixed to it, and connected by a link 57 to a lever 58, pivotally supported at 59, and connected to a link 60, which is connected with a pusher 61. When the shaft 7 is not being driven, the tobacco is not fed from the plate 52 to the sizing box.

The operation will now be apparent to those skilled in this art and is as follows:

The tobacco, in the form of either long or short filler, is intermittently fed in small quantities less than a bunch charge from the plate 52 to the sizing box 21. During this operation the worm shaft 6 and shaft 7 are revolving and the rock shaft 11 is being rocked. After each small quantity of tobacco is fed to the sizing box, the sizing plunger 15 is rocked downwardly pressing such small quantity to the lower part of the sizing box against the closure formed by the lever 22. This pressing operation is repeated for each small quantity until the bunch charge is built up to a predetermined height for a single bunch charge. When this point is reached, the sizing plunger 15 fixed to the shaft 11, as is the lever 14, will be arrested at an earlier point in its movement than when moving to press the preceding small tobacco quantities, while the lever 10 will continue its stroke through crank 8, link 9. The set screw 19 will contact the lever 16, bearing against the arm 39 to rock it out of the path of the lever 40, thereby permitting the roller 47 to move into the path of the cam 48, thus rocking the lever 49 to effect the release of the clutch 5, and thereby stopping the feed of tobacco filler.

In order to provide for the release of the hook 26 from the bottom closure 22 of the sizing box, the hook 26 on the lever 27 is moved downwardly with such lever to release the arm 25. The lever 27 is operated through link 31, lever 32 and cam 33.

The shaft 35 makes one revolution during the cycle of the machine. The shaft 4 is continuously revolved and is driven at a faster rate than the shaft 35.

The bunch charge is moved out of the sizing box by an ejecting plunger, similar to that shown in our Patent Number 2,243,699 of May 27, 1941, to be received in the pocket of a rolling apron for the application of a binder in a conventional manner. The ejecting plunger moves downward-

ly as described in our Patent No. 2,243,699, causing the bottom closure of the sizing box to be moved into its open position. The machine completes one cycle and the tobacco feed stops. The machine is started by pushing the lever 40 rearwardly, thereby rocking the lever 42 to move the link 44 downwardly, and cause the lever 51 to cause engagement of the clutch 5. When the link 44 moves downwardly, the lever 45 is rocked downwardly, moving roller 47 out of the path of the cam 48, thereby allowing lever 49 to move. The clutch 5 is released when the roller 47 is in the path of the cam 48.

It now will be apparent that the sizing plunger is actuated by a yielding driving connection to measure the height of a bunch charge, and when the bunch charge has been built up to the required height, means is actuated by the yielding driving connection to stop the feed of tobacco to the sizing box.

Having thus described our invention, what we claim as new and desire to secure by Letters Patent is:

1. Mechanism for making cigar bunch charges, comprising a sizing box to which filler is intermittently fed in small quantities to build up a bunch charge, a sizing plunger to press each small quantity downwardly as it is received in the sizing box, two relatively movable tensioned members, one of which is in fixed relation with said sizing plunger to raise and lower it, driving means for the other of said members, the filler on reaching a height in said sizing box corresponding to a single bunch charge causing a change in relation of said members, and means controlled by such change in relation of said members to control said driving means to stop said feed as soon as a single bunch charge has been built up in the sizing box.

2. Mechanism for making cigar bunch charges, comprising a sizing box to which filler is intermittently fed in small quantities to build up a bunch charge, a movable closure for the bottom of said sizing box, means to lock said closure in closed position during the building up of a bunch charge, means to release said locking means when a bunch charge has been built up, a sizing plunger to press each small quantity towards the closure as it is received in the sizing box, two relatively movable tensioned members, one of which is in fixed relation with said sizing plunger to raise and lower it, driving means for the other of said members, the filler on reaching a height in said sizing box corresponding to a single bunch charge causing a change in relation of said members, and means controlled by such change in relation of said members to control said driving means to stop said feed as soon as a single bunch charge has been built up in the sizing box.

3. Mechanism for making cigar bunches, comprising a sizing box to which filler is intermittently fed in small quantities to build up a bunch charge, a rock shaft, a member fixed to said rock shaft, a member loosely mounted on said rock shaft, yielding means tending to retain said members in fixed relation, a sizing plunger fixed to said rock shaft to press against each small quantity as it is received in the sizing box, driving means for said loosely mounted member and means to stop said driving means when the filler in the sizing box reaches a predetermined height.

4. Mechanism for making cigar bunches, comprising a sizing box to which filler is intermittently fed in small quantities to build up a bunch charge, a rock shaft, a lever fixed to said rock

shaft, a lever loosely mounted on said rock shaft, yielding means tending to retain said levers in fixed relation, a sizing plunger fixed to said rock shaft to press against each small quantity as it is received in the sizing box, driving means for said loosely mounted lever, and means to stop said driving means when the filler in the sizing box reaches a predetermined height.

5. Mechanism for making cigar bunches, comprising a sizing box to which filler is intermittently fed in small quantities to build up a bunch charge, a rock shaft, a member fixed to said rock shaft, a member loosely mounted on said rock shaft, yielding means tending to retain said members in fixed relation, a sizing plunger fixed to said rock shaft to press against each small quantity as it is received in the sizing box, driving means for said loosely mounted member, a trip lever on said fixed member, means carried by said loosely mounted member to actuate said trip lever when a predetermined height of filler is built up in the sizing box, and means actuated by said trip lever to stop said driving means.

6. Mechanism for making a bunch charge, comprising a sizing box, means to feed tobacco in small quantities to the sizing box to build up a mass not more than a bunch charge, a sizing plunger, a yielding driving connection to actuate the sizing plunger to measure the height of the bunch charge, and means actuated by said driv-

ing connection to stop the feed of tobacco when a single bunch charge has been built up to the required height.

7. Mechanism for making a bunch charge, comprising a sizing box, means to feed tobacco in small quantities to the sizing box, a sizing plunger, a rock shaft on which said plunger is fixed, a lever fixed on said rock shaft, a lever loose on said rock shaft, a spring connected with said levers, a screw adjustable on said loose lever, a tensioned trip lever on said fixed lever in the path of said screw, and means actuated by said trip lever to stop the tobacco feeding means.

10 8. Mechanism for making a bunch charge, comprising a sizing box, means to feed tobacco in small quantities to the sizing box, a sizing plunger, a rock shaft on which said plunger is fixed, a lever fixed on said rock shaft, a lever loose on said rock shaft, a spring connected with said levers, a screw adjustable on said loose lever, a tensioned trip lever on said fixed lever in the path of said screw, means actuated by said trip lever to stop the tobacco feeding means, a tensioned lever forming a closure for the bottom 15 20 25 of the sizing box, a locking lever cooperating with said closure to lock it in closed position and timed means to release said locking lever.

JOSEPH W. GILES.

WILLIAM J. GILES.
